CALIFORNIA, A CORPORATION OF CALIFORNIA

GAS LIFT FOR OIL WELLS

Application filed April 18, 1927. Serial No. 184,492.

Our invention relates to well pumps and particularly a pump in which the liquid is lifted to the surface of the ground by gas.

The ordinary gas-lift consists of a liquid delivery tube which is extended from the surface of the ground to a point below the liquid level. A pipe or equivalent is provided for delivering gas under pressure to the lower end of the liquid delivery tube.

10 The gas passes upward through this delivery tube and carries the liquid therewith.

It is very undesirable to place a back-pressure on the oil bearing sands of an oil well for the reason that it tends to diminish the 15 yield of the well.

One of the objects of our invention is to provide a gas-lift in which no back-pressure will be placed on the bearing formation.

Another object of the invention is to provide 20 a gas-lift in which there will be no back-flow of liquid from the gas-lift into the bearing formation.

In wells where the yield is small we find it more economical to pump intermittently.

25 It is one of the objects of this invention to provide a gas-lift which is adapted to operate either continuously or intermittently.

A still further object of the invention is to provide 30 a gas-lift in which the natural gas of the well assists in raising the liquid to the surface of the ground.

Other objects and advantages of the invention will be made apparent in the following description.

35 Our invention may be best understood by referring to the drawings in which a preferred form is illustrated.

Referring to the drawings:

40 Fig. 1 is a vertical section showing the gas-lift installed in a well.

Fig. 2 is an enlarged vertical section showing the gas-lift, per se.

45 Fig. 3 is a cross section taken on the line 3-3 of Fig. 2.

Fig. 4 is a cross section taken on the line 4-4 of Fig. 2.

Fig. 5 is a cross section taken on the line 5-5 of Fig. 2.

50 Fig. 6 is a cross section taken on the line 6-6 of Fig. 2.

The form of the invention shown in the drawings is adapted to be installed in a well 11 which may be an oil well or a water well. In this presentation of the invention we will consider that the well 11 is an oil well. 55 Installed in the well 11 is a well casing 12, the upper end of which is provided with a casing head 13. The liquid level of the well is indicated at A-A in Fig. 1. Extended downward from the upper end of the well 11 casing 12 is a delivery pipe 15. The upper end of the delivery pipe 15 above the casing head 13 is provided with an elbow 16 to which a pipe 17 is joined, this pipe 17 extending to a suitable storage or place of 60 utility for the liquid. Attached to the lower end of the delivery pipe 15 is the gas-lift 65 of our invention per se, this gas-lift being indicated, as a whole, by the numeral 18.

Referring particularly to Fig. 2, secured 70 to the lower end of the delivery pipe 15 is a coupling 20. This coupling 20 has a pressure-gas member 21 connected thereto which extends downward therefrom. The lower end of the pressure-gas member 21 extends 75 a great distance below the liquid level of the well. The submergence of the lower end of this pressure-gas member may be 500 to 1000 feet. At the extreme lower end thereof is a main valve which is in the form of a conical seat 22 and a ball 23. The purpose of this main valve is to permit a flow of liquid into the lower end of the pressure-gas member 21 but to prevent a flow of the liquid from the pressure-gas member in a reverse direction. 80

A supporting pin 24 extends diametrically across the pressure-gas member 21 immediately above the main valve. Supported by this supporting pin 24 and extending upward in a chamber 25 defined inside the member 21 above the main valve is a delivery tube 26. The delivery tube 26 is of a substantially smaller diameter than the pressure-gas member 21 and extends upward through the chamber 25 to a point above the coupling 20. Near the upper end of the pressure-gas member 21 and between it and the delivery tube 26 is a packer 27 defining the upper end of the chamber 25. The packer 27 consists of a lower ring 28 which is lowered into the an- 85 90 95 100

5 nular space between the two parts in consideration and is supported by a split ring 29 which rests in an internal groove of the pressure-gas member 21. A rubber packer 30 is placed above the lower ring 28, and screwed onto the delivery tube 26 is an upper ring 32 which compresses the packing so as to provide a tight seal at this point between the delivery tube 26 and the pressure-gas member 21. 10 The closing of the upper end of this space between the pressure-gas member 21 and the delivery tube 26 forms a pressure-gas passage 34. By an inspection of the lower part of Fig. 2 it will be seen that this 15 pressure-gas passage 34 is in communication with the interior of the delivery tube 26 by way of the lower end of it.

Surrounding the pressure-gas member 21 just below the coupling 20 is an outer member 20 in the form of a shell 35. The shell 35 forms an annular space around the pressure-gas member 21, which space serves as a well-gas exhaust passage 36. The shell 35 is secured to the pressure-gas member 21 at the 25 lower end thereof by a series of spaced spot-welds 37 and also by a means shown clearly in Fig. 4. The pressure-gas member 21 and the shell 35 are drilled with aligning holes 38 and 39. The two parts are then welded together, the holes being filled with welding material as indicated at 40. This means rigidly secures these two parts together. A seal at the upper end of the shell 35 is provided by engagement of the lower end of the coupling 20 with the upper end of the shell. The 30 contacting surfaces may be ground so that a good joint will result.

The lower end of the shell 35 is provided with a packer 42. This packer 42 is held in 40 place on the shell 35 by a special collar 43 which is screwed onto the lower end thereof. The packer is so designed that it will engage the well casing 12 and provide a seal between the well casing 12 and the shell 35. The 45 space in the well casing 12 around the gas-lift 18 and the delivery pipe 15 is thus converted into a pressure-gas chamber 44. Gas under pressure is supplied to this pressure-gas chamber 44 by means of a pressure-pump 50 connected to the casing head 13 by a pipe 46.

The pressure-gas chamber 44 is connected to the pressure-gas passage 34 by pressure-retaining valves 47 which are illustrated in 55 detail in Fig. 4. The welded bosses 40 which are used to attach the pressure-gas member 21 and the shell 35 together are drilled with radial openings 48. The pressure-relief valves each have a passage 49 provided 60 therethrough, which passage provides a seat against which a ball 50 is resiliently held by means of a compression spring 51. These parts are installed in the passage 49 through the inner ends of the valves 47 and are retained therein by an apertured plug 53. The

purpose of the pressure-retaining valves 47 is to prevent any passage of pressure-gas from the pressure-gas chamber 44 into the pressure-gas passage 34 unless a predetermined pressure is exceeded. I prefer to have 70 the minimum pressure at which gas will pass through these valves 47 to be 100 pounds. Usually we employ greater pressure, but in some cases less pressure may be used. The valves 47 are thus pressure-operated by increasing the pressure supplied to the upper 75 end of the pressure-gas chamber 44.

Returning our attention to Fig. 2, it will be seen that the packer 42 is placed slightly above the liquid level A—A of the well. It will further be seen that the well-gas exhaust passage 36 is at its lower end connected to the interior of the well. The upper end of the well-gas exhaust passage 36 is communicated with the interior of the delivery pipe 15 by 80 means of ducts 55 provided in the upper end of the pressure-gas member 21. A check valve is provided at the upper end of the well-gas exhaust passage 36 to prevent a reverse flow from the interior of the delivery 85 pipe 15 into the interior of the well below the packer 42. This check valve consists of a ring-valve member 56 which rests in an annular channel 57 which is formed around the ducts 55. therein. The level of the liquid in the pressure-gas passage 34 is forced downward to the lower end of the delivery tube. The main valve being closed at this time prevents any 5 of the liquid from backing into the interior of the well and therefore prevents a back-pressure being placed on the formation. The pressure-gas upon reaching the lower end of the delivery tube 26 flows upward there- 10 through and forces the oil in the delivery tube upward into the delivery pipe 15 in which it is conducted to the surface of the ground. We wish to make it quite clear that any excess of pressure at the lower end of the 15 pressure-gas member 21 securely retains the main valve closed. This is true when the gas-lift is being used on low-pressure formations. If the gas-lift, on the other hand, is used in wells having high-pressure formations, the 20 pressure of the formation may be greater than the gas-pressure employed. In such cases the pressure in the well will be greater than the pressure in the pressure-gas member 21 and even though there is a flow of pres- 25 sure-gas therethrough, there will also be an ingress of liquid from the lower end thereof. In such a case there will be no back-pressure placed on the formation because the pressure of the pressure-gas is not sufficient to cause it. 30 Any well-gas which may accumulate in the interior of the well passes upward around the pressure-gas member 21 to the space above the oil level A—A and below the packer 42. This well-gas is free to pass upward through 35 the well-gas exhaust passage 36 and if it is of sufficient pressure will open the ring-valve member 56 and flow into the interior of the delivery pipe 15. This well-gas will inter- 40 mingle with the liquid being raised and will assist in elevating it to the surface of the ground.

On wells of low formation-pressure and where the yield of liquid is quite small, the gas-lift cannot be economically operated over 45 a long period of time. This is true where the pressure of the pressure-gas in order to elevate the liquid to the surface of the ground must be greatly in excess of the formation pressure. In such wells it is advantageous 50 to operate the gas-lift intermittently. When the flow of pressure-gas is arrested, the pressure in the delivery tube and pressure-gas member is reduced to less than the pressure in the interior of the well. The main valve 55 will open and liquid will flow into the lower end of the chamber 25 of the pressure-gas member 21 and into the delivery tube 26, filling them to the level of the well. After a short period of time which is sufficient to 60 allow this ingress to take place, the pressure-gas is again made to flow and the same operation of lifting the liquid, as previously explained, is repeated.

From the foregoing description it should 65 be apparent that the gas-lift of our invention

is an important advance in the art in a number of respects. First, there is absolutely no back-pressure on the liquid-bearing formations or no back-flow of liquid thereinto. In the second place, the gas-lift is especially 70 suitable for intermittent operation and on low-pressure formations is found to be very economical. In the third place, the well-gas is utilized to assist the pressure-gas in lifting the liquid to the surface of the ground. This 75 is quite important because it conduces to economy and also because it serves as an exhaust means for the well-gas which prevents an accumulation of it, and consequently a back-pressure which would under ordinary 80 circumstances lower the level A—A of the liquid in the well 11.

The apparatus illustrated in the drawings and described heretofore is a preferred form, but obviously is not the only form in which 85 the invention may be embodied. The gas-lift is made entirely of pipes, which is found to be economical. The novel parts of the invention are briefly enumerated as follows:

First, it is necessary to have a liquid delivery means through which liquid is delivered to the surface of the ground. In the form of the invention illustrated this liquid delivery means is in the form of the delivery pipe 15 and the delivery tube 26. The main valve 90 at the lower end of the pressure-gas member is also important, although not essential when pumping continuously rather than intermittently. It is also essential to have a pressure-gas supply means. This pressure-gas supply 95 means in the drawings is provided by the pump 45, the pipe 46, and the pressure-gas chamber 44. Another important part is the well-gas conveying means which conveys the well-gas from the interior of the well to the 100 interior of the delivery pipe 15. In addition to this, the pressure-retaining valves 47 and the check valve at the upper end of the well-gas exhaust passage are important. From 105 this brief explanation of the essential parts it should be very evident that any design which provides any of these parts in various combinations comes within the scope of this invention.

We claim as our invention:

1. A gas-lift comprising: a liquid delivery means adapted to be extended into a well, the lower end extending below the liquid level of said well; a main valve near the lower end of said liquid delivery means for preventing liquid from flowing from said liquid delivery means into said well; pressure-gas supply means for supplying pressure-gas to the lower end of said liquid delivery means; and well-gas conveying means for conveying well-gas 120 from the space in said well to the interior of said liquid delivery means at a point above the liquid level of said well.

2. A gas-lift comprising: a liquid delivery means adapted to be extended into a well, the 125

lower end extending below the liquid level of said well; a main valve near the lower end of said liquid delivery means for preventing liquid from flowing from said liquid delivery means into said well; pressure-gas supply means for supplying pressure-gas to the lower end of said liquid delivery means; well-gas conveying means for conveying well-gas from the space in said well to the interior of said liquid delivery means at a point above the liquid level of said well; and a well-gas check valve for preventing a reverse flow through said well-gas conveying means.

3. A gas-lift comprising: a liquid delivery means adapted to be extended into a well, the lower end extending below the liquid level of said well; a main valve near the lower end of said liquid delivery means for preventing liquid from flowing from said liquid delivery means into said well; a packer surrounding said liquid delivery means near the liquid level of said well, said packer providing a pressure-gas chamber around said liquid delivery means; a pressure-gas member for supplying pressure-gas from said pressure-gas chamber to the lower end of said liquid delivery means; and well-gas conveying means for conveying well-gas from the space in said well to the interior of said liquid delivery means at a point above the liquid level of said well.

level of said well.

4. A gas-lift comprising: a liquid delivery means adapted to be extended into a well, the lower end extending below the liquid level of said well; a main valve near the lower end of said liquid delivery means for preventing liquid from flowing from said liquid delivery means into said well; a packer surrounding said liquid delivery means near the liquid level of said well, said packer providing a pressure-gas chamber around said liquid delivery means; a pressure-gas member for supplying pressure-gas from said pressure-gas chamber to the lower end of said liquid delivery means; well-gas conveying means for conveying well-gas from the space in said well to the interior of said liquid delivery means at a point above the liquid level of said well; and a well-gas check valve for preventing a reverse flow through said well-gas conveying means.

5. A gas-lift comprising: a liquid delivery means adapted to be extended into a well, the lower end extending below the liquid level of 55 said well; a main valve near the lower end of said liquid delivery means for preventing liquid from flowing from said liquid delivery means into said well; a packer surrounding 60 said liquid delivery means near the liquid level of said well, said packer providing a pressure-gas chamber around said liquid delivery means; a pressure-gas member surrounding said liquid delivery means for supplying pressure-gas from said pressure-gas 65 chamber to the lower end of said liquid de-

livery means; well-gas conveying means for conveying well-gas from the space in said well to the interior of said liquid delivery means at a point above the liquid level of said well; and a well-gas check valve for preventing a reverse flow through said well-gas conveying means.

6. A gas-lift comprising: a liquid delivery means adapted to be extended into a well, the lower end extending below the liquid level of said well; a main valve near the lower end of said liquid delivery means for preventing liquid from flowing from said liquid delivery means into said well; pressure-gas supply means for supplying pressure-gas to the lower end of said liquid delivery means; walls forming a well-gas conveying passage connected to said well and to the interior of said liquid delivery means; and check means for preventing a flow from the interior of said liquid delivery means into said well-gas conveying passage.

7. A gas-lift comprising: a liquid delivery means adapted to be extended into a well, the lower end extending below the liquid level of said well; a main valve near the lower end of said liquid delivery means for preventing liquid from flowing from said liquid delivery means into said well; pressure-gas supply means for supplying pressure-gas to the lower end of said liquid delivery means; walls forming a well-gas conveying passage connected to said well and to the interior of said liquid delivery means above the liquid level of said well; and check means for preventing a flow from the interior of said liquid delivery means into said well-gas conveying passage.

8. A gas-lift comprising: a liquid delivery means adapted to be extended into a well, the lower end extending below the liquid level of said well; a main valve near the lower end of said liquid delivery means for preventing liquid from flowing from said liquid delivery means into said well; pressure-gas supply means for supplying pressure-gas to the lower end of said liquid delivery means; walls forming a well-gas conveying passage around the lower end of said liquid delivery means and connected to said well and to the interior of said liquid delivery means; and check means for preventing a flow from the interior of said liquid delivery means into said well-gas conveying passage.

9. A gas-lift comprising: a liquid delivery means adapted to be extended into a well, the lower end extending below the liquid level of said well; a main valve near the lower end of said liquid delivery means for preventing liquid from flowing from said liquid delivery means into said well; pressure-gas supply means for supplying pressure-gas to the lower end of said liquid delivery means; walls forming a well-gas conveying passage around the lower end of said liquid delivery 120

means and connected to said well and to the interior of said liquid delivery means above the liquid level of said well; and check means for preventing a flow from the interior of said liquid delivery means into said well-gas conveying passage.

In testimony whereof, we have hereunto set our hands at Long Beach, California, this 8th day of April, 1927.

10 WILLIAM A. GAMMACK.
